DOOR LATCH

Andrew A. Kucher, Dayton, Ohio

Application November 17, 1936, Serial No. 111,263

16 Claims. (Cl. 292—127)

The present invention relates to door latches and more particularly to door latches of the free catch type.

One of the objects of the present invention is to provide a door latch in which the catch is urged in one direction by a spring and is provided with a camming surface and in which a manually operated device cooperates with the camming surface for moving the catch to another position against the action of the spring.

In the present invention, the catch mechanism is pivotally mounted and is arranged to hook with a shoulder for latching the same, and, another object of the present invention is to arrange the pivot for the catch mechanism and the point at which the catch engages the shoulder in substantially the same arc through which the pivot for the catch mechanism swings when the door is swung. In certain constructions such as refrigerator cabinets, a cabinet frame or door frame is utilized and such frame is provided with a covering. A further object of the invention is to secure the base for the catch to the covering and between the covering and the frame and to extend the operating handle mechanism for the catch through the covering.

A still further object is to dispose the catch mechanism in an opening in the frame and to utilize the side walls of the opening for preventing the displacement of the pivot for the catch.

The latch of the present invention includes a manual operated stem for releasing the catch and another object of the invention is to arrange the catch and stem in such manner that the catch will engage the stem and bind therewith to thereby limit the movement of the catch and stem.

Further objects and advantages will be apparent from the following description, reference being had to the accompanying drawing wherein a preferred form of embodiment of the present invention is clearly shown.

In the drawing:

Fig. 1 is a fragmentary sectional view of the corner of an insulated cabinet showing my improved latch in latching position;

Fig. 2 is similar to Fig. 1 but showing the latch in released position and showing part of the catch in section;

Figs. 3 and 4 are fragmentary sectional views taken on lines 3—3 and 4—4, respectively, of Fig. 1;

Fig. 5 is a fragmentary sectional view taken on line 5—5 of Fig. 3; and

Fig. 6 is a diagrammatic view of the swinging door, the pivoted catch and the stationary strike.

The cabinet herein shown is more clearly illustrated in my copending application Serial Number 102,368, filed September 24, 1936. In the present application, the cabinet is indicated by the numeral 20 and the door by numeral 21. The cabinet 20 is provided with a strike 23 which is notched as at 24 to provide a shoulder 25 for the nose 27 of catch 28. Catch 28 is pivotally mounted on a pin 29 and is urged into latching position by a spring 31. A manually operable stem 32 is associated with the catch 28 for retracting the same from the socket or notch 24. The stem 32 extends to the exterior of the door and is there provided with a handle 34 for actuating the same.

Referring more in detail to the drawing, the cabinet 20 includes a cabinet frame 35 formed of wood or the like. The metal lining 36 and the metal covering 37 is spaced from one another and this space is filled with insulating material 38. The lining 36 and the covering 37 are clamped to the frame 35 by breaker strips, one of which is shown at 40. These strips 40 are secured to the frame directly as by screws (not shown). The breaker strip 40 is notched to receive the strike 23 which is secured to the breaker strip by screws 42.

The door 21 includes a sheet metal outer cover in the form of a pan 44 providing a front wall 45. The material is bent rearwardly, to form narrow side walls 46, and then inwardly to form rear inwardly extending flanges 47. Thus the portions 45, 46 and 47 form a channel 48 within the outer frame edges of the door 21. A rectangular frame 49 is disposed within the door and forms a compartment for insulating material 50. This compartment is covered by the front 45 and the back panel 51.

Each side of the rectangular frame 49 includes a flat wood member 53 and a wood member 54 which is substantially trapezoidal shape in cross section. The members 53 are first inserted into the channel 48 and then the members 54 are secured to the members 53. A flexible gasket 56 is provided with a hook portion 57 which extends into grooves 58 formed in the flat member 53. Metal strips 59 lie flush with the back of members 53 and extend into the hook 57 for holding the gasket in position. A like gasket 61 having a hook 62 covers the edge of panel 51. This panel 51 is secured to the frame member 54 by screws (not shown). Four breaker strips, one of which is shown at 64, are secured to the sides of members 54 by screws (not shown). These breaker strips 64 overlie the metal strips 59 and the shank portions of the gasket hooks 62 and thereby hold

the gaskets 56 and 61 and the strips 59 in position.

The left side of the door, opposite the hinged side, is provided with a catch mechanism for co-operation with the strike 23 and its notch 24. The catch mechanism is carried by a base 66. This base 66 is formed of flat sheet metal which is cut and bent to form ears 67. The catch 28 extends between the ears 67 and is pivoted to the 10 ears by the pin 29. A groove or channel 68 is formed in the frame member 53 for receiving the base 66. The base is provided with an opening 70 for receiving a bushing 71. The bushing 71 is provided with a head 72 disposed on the outside of the door pan 44 and the shank 73 of the bushing, within the door, is threaded. A nut 74 is threaded on the shank 73 which nut when tightened securely clamps the bushing 71 and the base 66 in position on the pan 44. The frame member 53 is also cut-away as at 76 so as to receive the catch mechanism, the bushing 71 and the nut 74.

The left side of the door 21 is provided with two frame members 54. The inner ends of these members 54 are spaced from one another and aligned with the cut-away portion in frame member 53 to provide, with said cut-away portion, an opening 77. The catch 28 which is pivotally mounted on the pin 29 extends into opening 77 and through a hole 78 cut in breaker strip 64. The side walls 79 of the cut away portion 76 are spaced at such a distance from one another so as to function as retaining walls for preventing the displacement of pin 29.

35 An arm 81 is formed integrally with the catch 28 and the spring 31 engages the arm 81, through a washer 82, and normally urges the catch to the left and latch position. It will be apparent that when the door is being closed, the nose 27 of catch 28 will engage the strike 23, moving the catch to the right and compressing spring 31 and when the nose 27 is moved beyond the end of the notch or socket 24, the spring 31 will react to force the nose 27 behind the shoulder 25 of notch 24.

45 It will be noted from Figs. 1 and 6 that I have arranged the parts in such manner that the point at which the catch 28 engages the shoulder 25, when the door is closed, and the pivot for the catch lies in substantially the same arc of travel of the pivot when the door is swung. In fact, in the preferred embodiment, the said point lies slightly beyond this arc. The pivot of hinge for the door 21 is shown at 83 and the arc through which the pivot or pin 29 swings is indicated at 84. Therefore, a pull directly on the door tends to force the nose 27 farther into the notch. When the door is closed, the gaskets 56 and 61 are compressed and expansion of these gaskets will not tend to open the door. By this construction, a light spring 31 can be used. The tension of spring 31 need be sufficient only for moving the nose 27 behind the shoulder 25.

55 It will also be apparent that very little energy need be expended when it is desirable to open the door. It is necessary only to pull the nose 27 of latch 28 out of socket 24 and since the spring 31 is relatively weak, its tension is readily overcome.

70 Any suitable mechanism can be employed for moving the catch nose 27 out of socket 25. In the preferred embodiment, I have illustrated a pull type handle for moving the catch. A stem 32 is suitably secured to a handle 34. The stem 32 is guided by the bushing 71 and extends

through spring 31. The base of handle 34 extends into a recess 87 of bushing head 72. The inner end of stem 32 is milled flat at 89 on opposite sides thereof and these milled portions 89 extend between the tines 90 of the bifurcated arm 81 of catch 28. A pin 91 is suitably secured to the end of the stem 32 in camming relation with the rear sides 92 of tines 90 of arm 81. The portions 89 of stem being flat, are prevented from turning by the tines 90 and thus the pin 91 is maintained in proper position at all times. For smoother operation, the camming surfaces 92 may be disposed at an angle as is herein shown.

A very slight pull on handle 34 will cause the pin 91 to move the catch nose 27 out of socket 25. Ordinarily the spring 31 has sufficient tension to limit the movement of the catch while the door is being swung open by the movement of the handle. However, in view of the fact that it is desirable to use a light spring, it is desirable to directly mechanically limit the rocking of the catch. For this purpose, reference is made to Fig. 2 wherein the catch is shown in its extreme "pulled" position. It will be noted that I have arranged the yoke 94 of arm 81 so that it will engage and bind with the stem 32 and thereby limit further movement of the stem and the catch 28.

The latch mechanism is of the "free bolt" type. The catch 28 can move on its pivot while the stem 32 is maintained in the position shown in Fig. 1. When the door 21 is being closed, the strike 23, acting through the catch 28, will merely cause the compression of spring 31 without imparting movement to the stem 32. In order to accomplish this, the milled portion 89 of stem 32 is of sufficient length that the depressed washer 82 will not engage the stem when the stem is in its extreme inward position and the catch is in its extreme unlatching position.

If desirable a facing plate 95 can be attached to the breaker strip 64 as by screws 96. This plate 95 is provided with an opening 97 for receiving the catch nose 27.

In assembling the door, the catch mechanism is attached to the front pan 44. Then the four frame members 53 are inserted into the channel 48 formed by the edge of pan 44. The five frame members 54 are then secured to the frame members 53. Thus all of these parts cooperate to hold one another in position and since the base plate 66 fits within the groove 68 of frame 53 and abuts the side wall 46, of pan 44, and since the frame 53 is held in place by the flanges 47 of the pan 44, the single nut 74 is sufficient to rigidly secure the catch mechanism to the door.

From the foregoing, it will be seen that I have provided a latch which positively maintains its catch position and which cannot be released except by positive releasing movement by the releasing handle. Furthermore the construction is such that very little energy need be applied to release the latch. It is necessary only to pull the handle to release the latch and swing the door. Other advantages such as the limited number of parts, the ease of assembly, the ruggedness of construction and the low cost of manufacture will be readily apparent to those skilled in the art.

75 While the form of embodiment of the present invention as herein disclosed constitutes a preferred form, it is to be understood that other forms might be adopted, all coming within the scope of the claims which follow.

I claim:

1. In combination, a door frame and an outside covering for the frame; a latch base disposed against the inside wall of the covering and secured to the covering; a catch pivotally carried by the latch base; and means extending through the covering for actuating the catch. 5
2. In combination, a door frame and an outside covering for the frame; a latch base disposed between the frame and covering and secured to the covering; a catch pivotally carried by the latch base and having a part extending through the frame; and means extending through the covering for actuating the catch. 10
3. In combination, a hinged door including a door frame and an outside covering for the frame; a latch base having one portion thereof disposed between the frame and covering and held against the covering by the frame and having another portion secured directly to the covering; a catch pivotally carried by the latch base and having a part extending through the frame; and means extending through the covering for actuating the catch. 15
4. In combination, a door frame and an outside covering for the frame; a latch base; a catch pivotally carried by the base; a bushing extending through the covering and the latch base; means for securing the bushing, said base and covering with one another; and a stem within the bushing and operatively associated with the catch and extending through the covering. 20
5. In combination, a door frame and an outside covering for the frame; a latch base; a catch pivotally carried by the base; a bushing extending through the covering and the latch base; means for securing the bushing, said base and covering with one another; a spring normally urging the catch in one direction; and a stem within the bushing and having one end extending through the covering and having the other end operate upon movement to counteract the spring. 25
6. In combination, a door frame and an outside covering for the frame; a latch base; a catch pivotally carried by the base; a bushing ex- 30
- tending through the covering and the latch base; means for securing the bushing, said base and covering with one another; a spring surrounding the bushing and associated with the catch for normally urging the catch in one direction; and a stem within the bushing and having one end extending through the covering and having the other end operate upon movement to counteract the spring. 35
7. In combination, a door frame and an outside covering for the frame; a latch base; a catch pivotally carried by the base; a bushing extending through the covering and the latch base; means for securing the bushing, said base and covering with one another; a spring surrounding the bushing and associated with the catch for normally urging the catch in one direction; and a stem within the bushing, said stem having one end thereof extending through the covering, the other end of said stem being connected with the catch for moving the catch in the opposite direction. 40
8. In combination, a door frame having an opening, a latch base having a pivotal support extending into said opening, catch mechanism within the opening, a loose pivot for pivotally mounting the catch mechanism on the pivotal support, the opposite walls of the opening being disposed to prevent the displacement of the loose pivot. 45
9. In combination, pivotally mounted catch mechanism, a spring normally urging said mechanism in a certain direction, a guided stem manually movable for moving the catch mechanism in the opposite direction, said mechanism having a part adapted to engage the stem for limiting the movement of the mechanism by the stem. 50
10. In combination, pivotally mounted catch mechanism, a spring normally urging said mechanism in a certain direction, a guided stem manually movable for moving the catch mechanism in the opposite direction, said mechanism having a part adapted to engage the shank of the stem and bind therewith for preventing further manual relative movement of the stem. 55

ANDREW A. KUCHER.
